COMBINED CONTAINER AND TRAY FOR
TABLE FLATWAREArthur A. Eisenberg, New York, N. Y., assignor to
National Silver Company, New York, N. Y., a
corporation of New York

Application August 14, 1951, Serial No. 16,280

Term of patent 14 years

(Cl. D58—13)

To all whom it may concern:

Be it known that I, Arthur A. Eisenberg, a citizen of the United States, residing in the city, county, and State of New York, have invented a new, original, and ornamental Design for a Combined Container and Tray for Table Flatware, of which the following is a specification, reference being had to the accompanying drawing, forming a part hereof, in which:

Fig. 1 is a top plan view of a combined container and tray for table flatware embodying my new design;

Fig. 2 is a front elevation of the cover section thereof;

Fig. 3 is a side elevation of the cover;

Fig. 4 is a broken section taken on the line 4—4 of Fig. 1;

Fig. 5 is a plan view of the body section of the article;

Fig. 6 is a front elevation of the body section;

Fig. 7 is an end elevation thereof;

Fig. 8 is a broken section taken on the line 8—8 of Fig. 5;

Fig. 9 is a broken section taken on the line 9—9 of Fig. 5;

Fig. 10 is a broken section taken on the line 10—10 of Fig. 5; and

Fig. 11 is a broken section taken on the line 11—11 of Fig. 5.

I claim:

The ornamental design for a combined container and tray for table flatware, as shown.

ARTHUR A. EISENBERG.
